UNITED STATES PATENT OFFICE.

ROBERT A. GALLY, OF CINCINNATI, OHIO, ASSIGNOR TO THE BALDWIN COMPANY, OF CINCINNATI, OHIO.

PUMPER-SPRING.

1,271,458.

Specification of Letters Patent.

Patented July 2, 1918.

Application filed January 7, 1918. Serial No. 210,713.

To all whom it may concern:

Be it known that I, ROBERT A. GALLY, a citizen of the United States, and residing at Cincinnati, in the county of Hamilton and State of Ohio, have invented certain new and useful Improvements in Pumper-Springs, of which the following is a specification.

In this applicant's prior Patent #1,108,872, are shown "horizontal pumper bellows having their moving boards under side of said pumper" and "an arm or extension rigidly attached to and rising above its moving board" and "from the bearings at the top 10 of pumper arms are connecting rods or pitmen connecting downwardly." No springs were there shown for holding up and returning the pumpers, the use of springs for the return action of pumpers being well known, as usually applied directly to the moving board, and such were first used with these pumpers, being suspended below the pumpers by suitable brackets, but such position of the springs when the pumpers were 20 under side the main part of a horizontal grand piano, as then and now shown, were too conspicuous, and also in the way of a man when under the piano for inspecting or regulating the working parts, wherefore an improved disposition of the springs is 30 now set forth for use with the extended arm type of pumper, being especially useful when such pumpers are used adjacent the braces of a grand piano and their extended arms 35 are between the braces.

In the drawings Figure 1 shows a side view of a case of a grand piano having the side nearest the observer removed; and Fig. 2 is a plan view of the same case showing 40 how the two arms and their springs are disposed adjacent the braces of the piano, although the peculiar disposition of the springs with the extended arms of the pumpers may be used whether the piano is 45 with or without braces, and even when such pumpers and arms are used in other locations than piano cases and have these special spring devices, and also when such pumpers do not have their moving boards 50 underneath them, or where the pumpers are not horizontal.

The pumpers 1 have their moving boards 2 with arms 3 fixed with and extended from the moving ends of the said moving boards and toward and beyond their fixed boards 4. Pitmen 3^a or other connections are attached to the outer parts of the arms 3 to effect the movement of the moving boards 2 of the pumpers 1. From the outer part of each arm 3 to the fixed board 4 or some fixed part 60 attached with the fixed board 4, a spring 5 is connected to each arm 3 and so disposed as to pull each moving board 2 toward its corresponding fixed board 4. A convenient form of spring is the ordinary leaf spring 65 as 5 of the present showing, and this is very easily held in place by holes near the outer end of each leaf of the spring 5, and one of these holes engaged on a pin 6 on the fixed board 4 or part therewith such as the 70 attaching rail 7, and the other hole on a pin 8 of an extension 9 on arm 3 of the moving board 2.

When pumpers with arms as 3 are placed under a grand piano or the like, with the 75 arms 3 extending up within the main part of such piano, the springs 5 are conveniently disposed adjacent to and in the same plane with the braces 10 of the piano, as particularly well shown in Fig. 2, and when a brace 80 as 10 is at an angle to the main dimension of the case the springs may be similarly slanted, and with more widely separated braces may stand between them.

What I claim as my invention is:— 85

1. A player piano including a bellows pumper having a fixed board and a moving board, and an arm fixed to and extending from the said moving board toward and beyond said fixed board, and a spring connected from an outer part of said arm to a fixed part of the said player piano structure. 90

2. A bellows pumper having a fixed board and a moving board, and an arm fixed to and extending from the said moving board toward and beyond said fixed board, and a spring connected from an outer part of said arm to the said fixed board. 95

3. A player piano including a bellows pumper having a fixed board and a moving 100 board, and an arm fixed to and extending from the said moving board toward and be-

yond said fixed board, and a spring connected from an outer part of said arm to a fixed part of the said player piano structure and drawing the moving board toward the fixed board.

4. A bellows pumper having a fixed board and a moving board, and an arm fixed to and extending from the said moving board toward and beyond said fixed board, and a spring connected from an outer part of said arm to the said fixed board and drawing the moving board toward the fixed board.

5. A player piano including a bellows pumper having a fixed board and a moving board, and an arm fixed to and extending from the said moving board toward and beyond said fixed board, and a spring connected from an outer part of said arm to a fixed part of the said player piano structure, and a piano case having braces, the said pumper attached to the piano structure, and the springs and the upper parts of said arm positioned on a level with said braces and inside the said case.

6. A player piano including a bellows pumper having a fixed board and a moving board, and an arm fixed to and extending from the said moving board toward and beyond said fixed board, and a spring connected from an outer part of said arm to a fixed part of the said player piano structure, and a piano case having braces, the said pumper attached to the piano structure, and the springs and the upper parts of said arm positioned on a level with and inside the said case.

7. A player piano including a bellows pumper having a fixed board and a moving board, and an arm fixed to and extending from the said moving board toward and beyond said fixed board, and a spring connected from an outer part of said arm to a fixed part of the said player piano structure, and a horizontal form piano case having braces, the said pumper attached to the piano structure, and the springs and the upper parts of said arm positioned on a level with said braces and inside the said case.

8. A player piano including a bellows pumper having a fixed board and a moving board, and an arm fixed to and extending from the said moving board toward and beyond said fixed board, and a spring connected from an outer part of said arm to a fixed part of the said player piano structure, and a horizontal form piano case, the said pumper attached to the piano structure, and the springs and the upper part of said arm positioned on a level with and inside the said case.

9. A player piano including a bellows pumper having a fixed board, and a moving board having a greater and a lesser dimension, and an arm fixed to and extending from the said moving board toward and beyond

said fixed board, and a spring having a greater and a lesser dimension connected from an outer part of said arm to a fixed part of the said player piano structure, and a piano case having braces, the said pumper attached to the piano structure, and the springs and the upper parts of said arm positioned on a level with said braces and inside the said case, the greater dimension of the said pumper being similar in direction to the greater direction of the said case, and one of the said braces adjacent to the said spring, and the greater dimensions of the brace and spring being in similar direction one to the other and inclined to the said greater dimension of the case.

10. A player piano including a bellows pumper having a fixed board, and a moving board having a greater and a lesser dimension, and an arm fixed to and extending from the said moving board toward and beyond said fixed board, and a spring having a greater and a lesser dimension connected from an outer part of said arm to a fixed part of the said player piano structure, and a piano case having braces, the said pumper attached to the piano structure, and the springs and the upper parts of said arm positioned on a level with said braces and inside the said case, and one of the said braces adjacent to the said spring, and the greater dimensions of the brace and spring being in similar direction one to the other and inclined to the main dimension of the case.

11. A piano case having a greater and a lesser dimension, and a brace with a greater and a lesser dimension and extended within the outer dimensions of the said case at an angle to the greater dimension of the said case; a bellows pumper adjacent the said brace and having a greater and a lesser dimension, and its greater dimension similar in direction to the greater dimension of the said case, and a spring having a greater and a lesser dimension and combined with the said pumper and disposed in the same plane with the said brace, and the greater dimension of the said spring similar in its direction to that of the said brace.

12. A piano case having a greater and a lesser dimension, and a brace with a greater and a lesser dimension and extended within the outer dimension of the said case at an angle to the greater dimension of the said case; a bellows pumper adjacent the said brace and having a greater and a lesser dimension and a spring having a greater and a lesser dimension and combined with the said pumper and disposed in the same plane with the said brace, and the greater dimension of the said spring similar in its direction to that of the said brace.

13. A piano case having a greater and a lesser dimension, and a brace with a greater and a lesser dimension and extended within

the outer dimension of the said case; a bellows pumper adjacent the said brace; and a spring having a greater and a lesser dimension and combined with the said pumper; the said brace and spring having their greater dimensions in similar direction one

to the other and inclined to the greater dimension of the said pumper.
